UNITED STATES PATENT OFFICE.

MINNIE MORENO SLEDGE, OF GAINESVILLE, ASSIGNOR TO MAIER & BERKELE, OF ATLANTA, GEORGIA.

DESIGN FOR A SPOON.

SPECIFICATION forming part of Design No. 24,766, dated October 22, 1895.

Application filed April 29, 1895. Serial No. 547,575. Term of patent 3½ years.

To all whom it may concern:

Be it known that I, MINNIE MORENO SLEDGE, a citizen of the United States of America, and a resident of Gainesville, in the county of 5 Hall and State of Georgia, have made a certain new and useful Design for Spoons; and I do hereby declare the following to be a full, clear, and exact description of the invention, such as will enable others skilled in the art 10 to which it appertains to make and use the same, reference being had to the accompanying drawing, and to letters of reference marked thereon, which forms a part of this specification.

15 The drawing shows a front view of the spoon.

In about the center of the concave side of the bowl of the spoon is the representation of an open boll of cotton *a*, and at the extreme end of the handle opposite the bowl is a crown *b*. For a short distance below said crown the edges of the handle are curved, so as to form a substantially circular surface on the face, and the edges are bordered with a 25 vine-like curved figure, one of the tendrils projecting outwardly from the curved edge at *c*. One of the tendrils *d* on each edge curves outwardly, as shown, forming the shoulders of the major end of the tapering 30 portion *e* of the handle. Along the edge of

this tapering portion on the front of the spoon is a knurled line of pearl-like protuberances *f*. The edges of the handle between the bowl and the lower end of the tapered portion *e* of the handle are curved and ornamented along 35 the edge by a curved figure of vine-like shape, which is shown extended a short distance into the bowl. On the rounded portion of the handle, near the crown thereon, is a medallion design composed of circles, in the 40 center of which is the conventional representation of a phenix rising from her bed of flame and ashes.

The main features of this design are the representation of a crown, the cotton boll, 45 and the medallion design. The back of the spoon may be ornamented in any desired manner.

Having thus described my invention, what I claim as new, and desire to secure by Letters 50 Patent, is—

The design for a spoon substantially as herein shown and described.

In testimony whereof I hereunto set my hand in presence of two subscribing witnesses. 55

MINNIE MORENO SLEDGE.
